UNITED STATES PATENT OFFICE.

ROBERT E. PATCHEL, OF PHILADELPHIA, PENNSYLVANIA.

BLOWTORCH.

Application filed March 31, 1921. Serial No. 457,273.

To all whom it may concern:

Be it known that I, ROBERT E. PATCHEL,
a citizen of the United States, residing at
Philadelphia, in the county of Philadelphia,
5 and State of Pennsylvania, have invented
certain new and useful Improvements in
Blowtorches, of which the following is a
specification.

My invention relates to improvements in
10 blow-torches and has particular reference to
a blow-torch wherein electrical means are
employed to heat and vaporize a liquid fuel.

An important object of the invention is to provide an electrical heating element arranged in proximity to the vaporizing or heating chamber, the elements being disposed in a highly compact manner.

A further object of the invention is to provide means whereby the electrical heating element will not only serve to heat the liquid fuel to vaporize it, but will superheat the vapors from the fuel.

25 A further object of the invention is to provide a device of the above mentioned character, which may be conveniently held in the hand of the operator, and shifted to various positions, without liability of the improper discharge of the liquid fuel.

1 A further object of the invention is to
80 provide means to cut off the supply of
vaporized fuel to the burner tip, when de-
sired, the pressure of the vaporizing fuel
to be also regulated by the controlling of
85 current passing to the electrical heating ele-
ment.

Further objects and advantages of the invention will be apparent during the course of the following description.

40 In the accompanying drawings forming a part of this specification, and in which like numerals are employed to designate like parts throughout the same,

Fig. 1 is a central vertical longitudinal sectional view through a device embodying my invention,

Fig. 2 is a transverse section taken on line 2-2 of Figure 1.

Fig. 3 is a similar view taken on line 3-3 of Figure 1.

80 Fig. 4 is a similar view taken on line 4-4 of Figure 1.

Fig. 5 is a side elevation, parts in sectional vertical longitudinal section, of a second form of the invention.

Fig. 6 is a transverse section taken on line 6-6 of Figure 5,

Fig. 7 is a similar view taken on line 7-7 of Figure 5.

Fig. 8 is a plan view of a third form of the invention.

Fig. 9 is a central vertical longitudinal section through the same.

Fig. 10 is a side elevation of the device shown in Figure 9, with the burner tip mounted directly thereon, and.

Fig. 11 is a transverse section taken on line 11-11 of Fig. 9.

In the drawings, wherein for the purpose of illustration are shown preferred embodiments of my invention, attention being called first to Figs. 1 to 4 inclusive, the numeral 15 designates a tubular body portion, constituting the container for the liquid fuel. This tubular body portion is provided at its forward end with a head 16, having a longitudinal screw threaded opening 17, for the reception of a screw threaded extension or nipple 18, formed upon a burner head 19. The burner head has a flange 20, adapted to contact with the end of the head 16, and suitable packing 21 may be interposed between the flange and head, preferably in the form of a copper gasket. 70 75 80

The head 19 is provided with a longitudinal bore 22, Fig. 2, having an enlarged screw threaded portion 23 and a further enlarged screw threaded portion 24. A tubular valve seat 25 is screw threaded within the enlarged bore portion 23 and is provided at its forward end with a groove 26, for the reception of the end of a screw driver or the like, whereby, this tubular valve seat may be removed, when desired. The numeral 27 designates a burner tip, which is tubular and has a screw threaded shank 28, for insertion within the screw threaded bore portion 24, as shown. This burner tip may have a flange 29, to contact with the forward end of the head 19. The upper end of the burner head 19 is provided with a screw threaded recess 30, within which is arranged an exteriorly screw threaded tubular element or nipple 31, carrying a nut or head 32, which is polygonal, and hence may be readily turned by a wrench or tool. The tubular nipple 31 rotatably receives a cylindrical stem 33, the forward end of which may be provided with a flange 34, spun or turned out from the material thereof, and half of the stem is positioned in the tubular nipple. A compressible coil spring 35 surrounds the

upper end of the stem and is confined between a head 36 thereof and the nut 32. The stem 33 is therefore free to rotate, and is normally held by the spring 35, against 5 longitudinal movement in a forwardly direction, but should it be desired to quickly shut off the supply of gas to the burner tip, this may be accomplished by pressing the head 36 forwardly, as will be more fully 10 explained. The stem 33 is provided with a longitudinal screw threaded opening 37, receiving the upper screw threaded portion of a valve stem 38. The lower portion of this valve stem has an enlarged diameter and 15 is provided with longitudinal ribs or lugs 39, entering grooves 40. The valve stem carries at its forward end a valve 41, adapted to engage upon and within the tubular valve seat 25. It is thus seen that the valve stem 20 can not turn upon its longitudinal axis, but is free to move longitudinally. The valve stem may therefore be gradually adjusted by turning the head 36, or it may be quickly moved longitudinally to seat the valve 41, 25 by pressing the head 36 downwardly.

The numeral 42 designates a head or member, carrying an exteriorly threaded tubular nipple or extension 43, adapted to engage within the screw threaded opening of a head 30 44, formed upon the rear end of the tubular body portion 15. Packing 45, preferably in the form of a copper gasket, is interposed between the heads 42 and 44, as shown. The tubular nipple or extension 43 carries a tubular covering element 46 of an electrical 35 heating unit, 47 being the heating coil thereof having lead wires 48 and 49. The function of the covering element 46 is to prevent the liquid fuel from coming in direct contact with the coil 47, as is obvious.

The numeral 50 designates a gas outlet tube, preferably formed integral with the nipple 18, and in connection with a port or bore 51, leading to the bore 22, as shown. 45 The rear portion 52 of the outlet tube 50 has an increased diameter, and serves as a vaporizing and superheating chamber. The enlarged tubular portion 52 surrounds tubular covering 46, in spaced relation thereto.

50 At the rear side of the head 42 is an insulating block 53, secured to the head 42 by screws 54. The block 53 receives socket contacts 55 and 56, which are electrically connected with the wires 48 and 49, respectively. 55 Plugs 57 are secured to an insulating base 58 and adapted for insertion within the sockets 55 and 56, for effecting electrical connection. These plugs are connected with lead wires 59. An insulating cap 60 has an 60 opening 61 for the lead wires, and is secured to the base 58. Other suitable means may be employed to feed current to the wires 48 and 49.

Surrounding the tubular body portion 15 65 is a heat insulating jacket 62, which may be

formed of fiber or any other material which is a poor conductor of heat. A metallic ring 63 is sweated upon the tubular body portion 15, and screw threaded for engagement within the screw threaded end of the sleeve 70 62. The sleeve 62 is arranged in spaced concentric relation to the tubular body portion 15, forming an annular air space 64. The rear end of the sleeve is supported upon the rear end of the head 44, as shown. 75

The operation of this form of the invention is as follows: The tubular nipple 18 with the head 22 may be unscrewed from within the head 16, and the tubular body portion 15 which may be held in an upright 80 position, may be partly filled with liquid fuel, such as alcohol. The tubular nipple is then screwed into the screw threaded opening 17, to form a tight joint. The tubular body portion 15 preferably contains an 85 amount of alcohol, so that the level thereof will be slightly below the mouth of the enlarged portion 52 of the tube 50 when the device is arranged horizontally. When the device is inclined so that its forward end is 90 elevated, the liquid cannot escape through the tube 50, and when the device is inclined with its forward end depressed, the liquid passes to the lower end of the tubular body portion 15, exteriorly of the tube. The 95 length of the tube 50 therefore serves as a trap to prevent the improper discharge of the liquid fuel. The current is now supplied to the heating coil 47, which transmits heat through the enlarged tubular portion 52 to 100 the exterior thereof within the tubular body portion 15. This heat is transmitted to the alcohol which is readily vaporized and the vapors pass into the enlarged portion 52 of the tube 50 and are hence superheated by 105 travelling in direct contact around the tubular covering 46, as they pass forwardly through the tube 50 and bore 51. The pressure of the vaporized alcohol may be regulated by controlling the amount of current 110 supply to the heating element 47. The volume of gas supplied to the burner tip 27 may also be regulated by these means and also by turning the head 36 to adjust the valve 41. Should it be desirable to instantly 115 cut off the flow of gas from the burner tip, this may be accomplished by suddenly depressing the head 36, whereby the valve 41 is seated.

In Figures 5 to 7 inclusive, I have shown 120 a second form of the device embodying my invention. In this form the numeral 65 designates a tubular body portion or liquid container, which is identical with the part 15 of the first form. This tubular body portion carried the burner head 19, identical with the burner head described in detail in connection with the first form, it being 125 thought unnecessary to again describe the various parts of this burner head, it being 130

sufficient to state that the same bores, valve seat, valve, and operating means are employed.

Extending longitudinally through the tubular body portion 65 is a gas outlet tube 66, carried by the nipple 18 of the head 19, and discharging into the bore 51. The numeral 67 designates a coupling element, having a forwardly extending screw threaded tubular nipple 68, engaging in the screw threaded opening of the head 69 of the tubular body portion 65. Packing 70, preferably in the form of a metallic gasket, is interposed between the coupling element 67 and head 69. This coupling element carries a tubular gas generating chamber 71, the rear end 72 of which is closed. This chamber is in direct communication with the bore 73 of the coupling element 67. The gas outlet tube 66, which in this case has a uniform diameter, throughout its entire length, enters the generating chamber 71, in spaced concentric relation thereto, as shown.

The numeral 74 designates an electrical heating unit, having a body portion of insulating material and a heating coil 75 therein. The heating unit 74 is tubular and surrounds the tubular generating chamber 71, as shown.

The numeral 76 designates an insulating support, secured to the end of head 72 by a screw 77. The coil 75 has lead wires 78 and 79, connected with metallic tubular sockets 80 and 81 respectively, carried by the insulating support 76. These tubular sockets are adapted to receive the metallic plugs having connection with the lead wires.

The numeral 82 designates a heat insulating sleeve, surrounding the heating element 74 and associated elements, in spaced concentric relation, and having screw threaded engagement with the coupling 67, as shown at 83.

In operation, the tubular body portion 65 receives and holds the liquid fuel, such as alcohol, and a portion of this fuel passes into the vaporizing chamber 71, particularly when the device is inclined. In this chamber the liquid is subjected to the heating action of the coil 75, whereby it is vaporized and the vapors pass through the tube 66 to the burner tip of the burner head. The pressure of the gas generated is regulated by controlling the volume of current supplied to the coil 75, and also by manipulation of the valve 41.

In Figures 8 to 10 inclusive I have shown a device embodying some of the features of the prior devices but having a capacity for holding a larger volume of liquid fuel. In this form the numeral 82' designates a cylindrical shell or body portion, designed to receive and hold the alcohol. This shell is ordinarily stationary and hence is equipped with a base 83'. At its top the

shell 82' is provided with a depending boss 84, having a screw threaded opening 85, for receiving a screw threaded plug 86.

This plug carries a U-shaped gas outlet tube 87, one end of which leads into a bore 88.

The numeral 89 designates a tubular heating element, surrounding one leg of the U-shaped tube 87. This heating element embodies a coil 90, and lead wires 91, extending upwardly through the protecting tube 92. These wires pass through a bore 93, and lead to metallic sockets 94, carried by an insulating block 95. This block is suitably secured to the plug 86. Metallic plugs 95' are secured to an insulating base 96, and are adapted for insertion within the metallic sockets 94. Wires are secured to the metallic plugs 95'. An insulating cap 97 is carried by the insulating support 96, as shown. 85

The numeral 98 designates a T-shaped coupling, having a vertical bore 99, leading into the bore 88. This coupling has a horizontal bore 100, in communication with an enlarged bore 101, which is internally threaded. The numeral 102 designates a screw threaded recess, receiving a screw threaded nipple 103, which is tubular, and rotatably receives a tubular stem 104, the inner end of which has a flange 105. The tubular stem is turned by a head 106 and a spring 107 is interposed between this head and the head of the nipple 103. The numeral 108 designates a valve stem, carrying a valve 109. This valve stem is provided with ribs 110, slidably in grooves 111. The valve stem is thus free to move longitudinally but cannot rotate, and the valve stem has screw threaded engagement within the tubular stem 104, whereby the valve stem 105 may be adjusted longitudinally by turning the tubular valve stem or by moving the tubular valve stem longitudinally. The valve 109 is adapted to engage a tubular valve seat 111', held within the bore 101. 110 The coupling 112 has an extension entering the bore 101, and this coupling is connected with a flexible hose 113, carrying a burner tip or nozzle 114.

The operation of the device is as follows: 115 The shell 82' is suitably filled with alcohol or the like, and current fed to the heating coil 90. The vaporized alcohol rises in the shell and passes down through one arm of the outlet tube 87, and up through the other 120 arm into the port or bore 88. The gas will now pass through the bore 99, and by valve 109 through the coupling 112, and hose 113 to the burner tip 114. The valve 109 may be gradually adjusted by turning the tubular stem 104, or it may be quickly seated or closed by moving this tubular stem forwardly and longitudinally. 125

In Fig. 10 the device is identical with that shown in Fig. 9, except that the burner 130

4
tip 114 is mounted directly upon the discharge end of the coupling 98, thus dispensing with the flexible hose 113.

It is to be understood that the forms of 5 my invention herewith shown and described, are to be taken as preferred examples of the same, and various changes in the shape, size and arrangement of parts may be resorted to without departing from the spirit 10 of my invention or the scope of the subjoined claims.

Having thus described my invention, I claim:

1. A blow torch comprising, a tubular 15 body portion for holding a liquid fuel, a burner element connected with the tubular body portion, a tube extending longitudinally within the tubular body portion and having communication with the interior of 20 the burner element, and an electrical heating element arranged in proximity to the tube.

2. A blow torch comprising, a tubular body portion for holding a liquid fuel, a burner head mounted upon one end of the 25 tubular body portion, a tube connected with the burner head and extending longitudinally within the tubular body portion, and an electrically operated heating element for heating the liquid fuel within the tubular 30 body portion.

3. A blow torch comprising, a tubular body portion for holding liquid fuel and adapted to serve as a handle, a burner head mounted upon one end of the tubular body 35 portion, a tube extending longitudinally within the tubular body portion and secured to the burner head, and an electrical heating element arranged near and in concentric relation to a portion of said tube.

4. A blow torch comprising, a tubular body portion, a burner head secured to the forward end thereof, a tube connected with the burner head and extending longitudinally within the tubular body portion, and 45 an electrical heating element extending into said tube in spaced relation.

5. A blow torch comprising, a tubular body portion, a burner head carried by the forward end of the tubular body portion, a

tube secured to the burner head and extending longitudinally within the tubular body portion and having a rear portion of enlarged cross sectional area, an electrical heating element extending longitudinally into the enlarged portion of the tube, and 55 means to supply current to the heating element.

6. A blow torch comprising, a tubular body portion, a burner head having a shank to enter the forward end of the tubular body portion, a tube carried by the shank and extending longitudinally of the tubular body portion, a plug extending into the rear end of the tubular body portion, an electrical heating element carried by the plug 65 and extending within said tube, and means to supply current to the heating element.

7. A blow torch comprising, a tubular body portion to serve as a handle, a burner head carried by the forward end of the tubular body portion, a tube secured to the burner head and projecting into the tubular body portion, a heating element extending longitudinally within the tubular body portion in spaced concentric relation to a portion of the tube, means to supply current to the heating element, and a heat insulating sleeve surrounding the tubular body portion in spaced concentric relation and connected therewith.

8. A blow torch comprising, a burner head, having a longitudinal bore and a valve seat, a valve stem movable longitudinally within the bore and incapable of turning upon its longitudinal axis and having a valve, said 85 valve stem having its rear portion screw threaded, a tubular valve stem having a screw threaded bore to receive the screw threaded end of the valve stem and being mounted within the rear portion of the 90 burner head to turn and move longitudinally therein, and a spring to oppose the longitudinal movement of the tubular valve stem in one direction.

In testimony whereof I affix my signature.

ROBERT E. PATCHEL.
